UNITED STATES PATENT OFFICE.

DAVID P. GUISE, OF WILLIAMSPORT, PENNSYLVANIA, ASSIGNOR TO
JULIA H. GUISE, OF WILLIAMSPORT, PENNSYLVANIA.

DOUBLE-DRAFT KILN.

No. 828,285.

Specification of Letters Patent.

Patented Aug. 7, 1906.

Application filed October 20, 1905. Serial No. 283,649.

To all whom it may concern:

Be it known that I, DAVID P. GUISE, a citizen of the United States, residing at Williamsport, in the county of Lycoming and State of Pennsylvania, have invented certain new and useful Improvements in Double-Draft Kilns, of which the following is a specification, reference being had therein to the accompanying drawings.

10 This invention relates to kilns for burning bricks or other articles of clay or pottery.

The object of the invention is to produce a kiln in which articles can be burned with uniformity by firing at different times from opposite directions. Preferably the first firing is from a lower set of furnaces, the upper furnaces being entirely closed. Afterward the firing is from the upper furnaces, the lower furnaces being closed, as will be explained.

20 Figure 1 is a side elevation of a kiln embodying my invention, the earth being removed to show the underground portion.

Fig. 2 is a vertical central section of the kiln, the stack being omitted. Fig. 3 is a horizontal section on two planes, the left-hand portion being below the floor and the right-hand section being through the upper furnaces.

25 The numeral 1 indicates the body of the kiln, which, as shown, is cylindrical, with a domed top 2. This form is considered preferable, but is not essential.

The lower furnaces 3 are below the level of the ground for convenience. These furnaces have suitable grates 4 and ash-pits 5 of any approved construction. Leading 35 from the furnaces 3 there are tunnels 6, extending toward the center of the kiln, and connecting these there are smaller tunnels 7. All these tunnels are built in the fire-brick 40 foundation of the kiln, and the tunnels are so arranged as to conduct the heat developed in the furnaces to substantially all parts of the base of the kiln. The abutments 9 between the tunnels are built up of fireproof material. 45 The furnaces 3 are in the heavy base-wall A of the kiln.

Above the tunnels 6 and 7 there is a perforated floor 10. The holes 11 in this floor are directly above the tunnels 6 and 7, so that 50 the products of combustion are conveyed from the furnaces through the tunnels and holes to the interior of the kiln.

Above the floor 10 the kiln extends to a

sufficient height, according to the work desired, and the cover 2 incloses it.

55

In the domed cover 2 there are a number of openings 12. These openings 12 are ordinarily covered with covers 13. The heat from the furnaces 3 after passing through the tunnels and the floor-openings escapes largely 60 to the stack 14 through flue 15, which flue has closing dampers 17 near the kiln and near the stack. Now when bricks are stacked in the kiln, as usual, for burning, the fire from the furnaces 3 circulates through them, and most of the escape of smoke and gases is to 65 the stack. Holes 12 are also used as observation-holes, and if it at any time appears that the kiln is burning unevenly one or more of the covers to openings 12 is uncovered, thus 70 making a vent through which heat and flame rush, drawing the heat from other parts of the kiln to the opened vents in the dome. The heat can be thus controlled with great uniformity.

75

When it is considered that the lower furnaces have completed the burning as far as it is desirable for them to do so, the fires are drawn or suffered to die out, and the mouths of the furnaces 3 and ash-pits 5 are closed 80 and hermetically sealed, as by luting. Then furnaces 23, which had been before tightly closed and sealed, are opened, and fires are built therein.

Furnaces 23 are built in the upper walls B 85 of the kiln, and each furnace has a grate 24 and an ash-pit 25. The inner end of each furnace 23 extends to a bag wall or flue 26, which bag wall or flue is preferably of brick, closed at the bottom and opening at the top 90 directly under the outer edge of the dome 2. A central well 27 extends down through the middle of the kiln to the exit tunnel or flue 30 below the ground and leading to stack 14, as indicated in dotted lines, Fig. 1. This flue 95 30 is carefully closed, as by a damper 29, when the lower tier of furnaces is in operation.

The openings 12 are closed and luted when the upper furnaces are burning; but to dampen the fires or cool any part of the kiln any one or more of these holes may be opened.

The flame and heat from furnaces 23 go up 100 inside the bag-walls 26 and thence pass to the upper portion of the kiln, being drawn down 105 by the tunnel 30 and so to the stack.

The bricks C to be burned are piled within the kiln about the central well and without much regard to the openings 11 in the floor, as these holes should not be large enough to receive a brick, but will pass a current of heat and flame even if partly covered with bricks.

As the heat from the upper furnaces travels in reverse direction from that of the heat from the lower furnaces, it will have greatest effect on those bricks which were least burned by the action of the lower furnaces, and vice versa.

For convenience in filling and emptying the kiln a door 35 is provided, and a track 36 leads through the kiln and out of a similar door at the opposite side. The doors are closed and luted when the burning is going on. Brickwork is generally employed for closing such openings when preparing to burn a kiln.

I prefer that the upper furnaces shall outnumber the lower furnaces and that they shall not be directly over the lower furnaces, being thus more convenient of access and giving also a more thorough distribution of heat.

What I claim is—

1. A double-burning kiln having furnaces below the floor-level, flues from said furnaces leading toward the center of the kiln and opening through the floor into the kiln, a central flue near the top of the kiln and a stack

to which said central flue leads, a domed cover to the kiln having series of openings and covers 35 for the same, a second series of furnaces above the kiln-floor and opening under the sides of the dome, a draft-flue below the floor and leading from openings in the floor to the stack, and means for controlling the flues leading to 40 the stack, all combined.

2. In a double-burning kiln, the combination of an inclosing wall, a floor, and a cover, a furnace below the floor and flues leading therefrom to openings in the floor, a stack, 45 and a flue leading from the upper part of the kiln to the stack, a furnace above the floor-level and a flue leading therefrom to the upper part of the kiln, and a flue leading from the lower part of the kiln to the before-men- 50 tioned stack.

3. In a double-burning kiln, the kiln-wall, cover, floor, and stack, a furnace below the floor and flues leading therefrom to the lower part of the body of the kiln, a furnace above 55 the floor and flue leading therefrom to the upper part of the kiln, and exhaust-flues provided with dampers, leading both from the upper and from the lower part of the kiln to the same stack, all in combination. 60

In testimony whereof I affix my signature in presence of two witnesses.

DAVID P. GUISE.
